EDUCATIONAL GAME BOARD

Kenneth A. H. Gordon, Bedford, and Charles L. Chesnut,
Chappaqua, N.Y., assignors to The Reader's Digest
Association, Inc., New Castle, N.Y.

Filed July 3, 1972, Ser. No. 268,780

Term of patent 14 years

Int. Cl. D21—01

U.S. Cl. D34—5 SS

FIG. 1

FIG. 1 is a plan view of the left side of an educational game board showing our new design; and FIG. 2 is a right side plan view thereof.

The design shown in the figures is of no appreciable thickness.

We claim:

The ornamental design for an educational game board, as shown and described.
